Primary Examiner — Susan E Krakower*Assistant Examiner* — Michelle M Reeves(74) *Attorney, Agent, or Firm* — Weiss & Arons LLP(57) **CLAIM**

The ornamental design for a seat, as shown and described.

DESCRIPTION

FIG. 1 is a bottom isometric view of the seat showing the design;

FIG. 2 is a bottom plan view thereof;

FIG. 3 is a top plan view thereof;

FIG. 4 is a right side elevational view thereof;

FIG. 5 is a left side rear elevational view thereof;

FIG. 6 is a front elevational view thereof; and,

FIG. 7 is a rear elevational view thereof.

The broken lines shown in FIG. 2 illustrate a portion of the seat that forms no part of the claimed design.

1 Claim, 5 Drawing Sheets(56)
